UNITED STATES PATENT OFFICE.

WILLIAM W. KARRO, OF GREAT NECK, NEW YORK.

ROLLER-SKATE.

1,367,397.

Specification of Letters Patent.

Patented Feb. 1, 1921.

Application filed October 3, 1919. Serial No. 328,187.

To all whom it may concern:

Be it known that I, WILLIAM W. KARRO, a citizen of the United States, residing at Great Neck, in the county of Nassau and 5 State of New York, have invented new and useful Improvements in Roller-Skates, of which the following is a specification.

The object of my present sole invention is the provision of a roller skate of advantageous construction in which the parts are so combined that the skate may be expeditiously and easily changed in length so as to be adapted for use by persons having feet of materially different sizes.

15 To the attainment of the foregoing, the invention consists in the improvement as hereinafter described and definitely claimed.

In the accompanying drawings, hereby made a part hereof:

20 Figure 1 is a side elevation of a roller skate constituting the best practical embodiment of my invention that I have as yet devised.

Fig. 2 is a longitudinal vertical section of 25 the same.

Fig. 3 is a transverse section taken in the plane indicated by the line 3—3 of Fig. 2.

Fig. 4 comprises disconnected detail views of the straps complementary to the skate.

30 Fig. 5 is a detail view of a feature herein-after explicitly referred to.

Similar numerals of reference designate corresponding parts in all of the views of the drawings.

35 Among other elements my novel skate comprises a body 1 having a heel-receiving portion 2 in the side walls of which are slots 3. Carried by the heel portion 2 is a hanger 4 in which is mounted a ground wheel 5

40 which is preferably of considerable diameter, and is provided with an appropriate cushioning tire 6. Also carried by the portion 2 of the body 1 is a comparatively heavy combination mud-guard and brake 7.

45 This element, by virtue of its arrangement, is adapted to serve under normal conditions as a mud-guard, and is also adapted when the wearer raises the forward portion of the skate, to engage the pavement or surface 50 traversed by the skate, and thereby serve as an effective emergency brake. Complementary to the heel portion 2 of the body 1 are straps 8 and 9; the said straps being equipped with hooks 10 to engage in the

55 slots 3, and one of the straps being provided with a keeper-loop 10^x, and the other

with a lever-hook 11 adapted to be positioned in the keeper-loop and then swung back upon its strap so as to preclude casual disconnection of the strap.

60 The forward portion of the body 1 is longitudinally slotted at 11^a, and on said body portion are pendent bearings 12 and 13; the bearing 12 serving to support the forward end of a longitudinally threaded 65 shaft 14, and the bearing 13 carrying a transversely disposed worm 15 which is adapted at one end for the application of a key lever or other means through the medium of which it may be conveniently 70 turned about its axis. The shaft 14 is provided at its rear end with a worm gear 16 intermeshed with the worm 15.

75 Superimposed upon the forward portion of the body 1 is the longitudinally-adjustable toe-engaging piece 17 of the skate, and adjustable as a unit with the toe-engaging piece 17 is a mud-guard 18 and a ground wheel 19; the ground wheel 19 being similar to the ground wheel 5 and being 80 mounted in hangers 28 that are fixed with respect to the toe-engaging piece 17 and the mud guard 18. Carried by the toe-engaging piece 17 and movable with the toe-engaging piece 17, the mud guard 18 85 and the hangers 28 is a pendent lug 21 in which is a threaded bore 22 that receives the threaded shaft 14. Manifestly when the worm 15 is turned in one direction about its axis, the toe-engaging piece 17 and the 90 parts carried thereby will be moved forward, while a reverse rotation of the worm 15 will be attended by rearward movement of the toe-engaging piece 17 and the elements carried thereby; also the co-acting 95 worm 15 and worm gear 16 may be depended upon to adjustably fix the toe-engaging piece 17 and the parts carried thereby with respect to the body 1, so that the provision of extraneous means for said purpose 100 is unnecessary.

It will be readily apparent from the foregoing that by virtue of my improvement, a roller skate may be expeditiously and easily fitted to feet of different sizes, and this without in any measure detracting from the utility of the skate or the support that it affords to a skater.

Having described my invention, what I claim and desire to secure by Letters-Pat- 110 ent, is:

1. In a roller skate, the combination with

a wheel-supported body having in its forward portion a longitudinal slot and on said portion spaced pendent bearings, a threaded shaft journaled in the forward bearing and equipped on its rear portion with a worm gear, a worm journaled in the rear bearing and intermeshed with said worm gear, a toe-engaging piece adjustable longitudinally on the body and having a pendent lug disposed in the body slot and in which is a threaded bore receiving the threaded shank, hanger means carried by and adjustable with said toe-engaging piece, a mud-guard also carried by and adjustable with the toe-engaging piece and one of the supporting wheels mounted in said hanger means.

2. In a roller skate, the combination with a wheel supported body having in its forward portion a longitudinal slot and on said portion spaced pendent bearings, a threaded shaft journaled in the forward bearing, a toe-engaging piece adjustable longitudinally on the body and having a pendent lug disposed in the body slot and in which is a threaded bore receiving the threaded shaft, 20 hanger means carried by and adjustable with the toe-engaging piece and one of the supporting wheels mounted in said hanger means.

In testimony whereof I affix my signature. 30

WILLIAM W. KARRO.
